UNITED STATES PATENT OFFICE.

ARTHUR J. BAXTER, OF SENECA, KANSAS.

SAFETY-RAZOR.

1,307,652.

Specification of Letters Patent. Patented June 24, 1919.

Application filed March 5, 1918. Serial No. 220,528.

To all whom it may concern:

Be it known that I, ARTHUR J. BAXTER, citizen of the United States, residing at Seneca, in the county of Nemaha and State of 5 Kansas, have invented certain new and useful Improvements in Safety-Razors, of which the following is a specification.

This invention relates to an improved safety razor and has as its primary object to 10 provide a device of this character which will be simple, durable, compact and inexpensive.

The invention has as a further object to provide a construction wherein the detachable blade holder may be struck at one operation from a single piece of material and wherein the said holder will be equipped with a plurality of resilient fingers or tongues for removably holding the blades 20 firmly in position.

And the invention has as a still further object to provide an arrangement wherein the handle of the device will be formed to carry a supply of the blades as well as the 25 blade holder.

Other and incidental objects will appear as the description proceeds and in the drawings, wherein I have illustrated the preferred embodiment of the invention, and 30 wherein similar reference characters designate like parts throughout the several views:

Figure 1 is a side elevation showing the inclined position of the blades upon the blade holder of the device,

Fig. 2 is a bottom plan view more particularly bringing out the arrangement of the blades with respect to each other upon the blade holder,

Fig. 3 is a sectional view taken on the line 40 3-3 of Fig. 2 and looking in the direction of the arrows, this view particularly showing the mounting of the blades,

Fig. 4 is a side elevation showing the blade holder detached with the blades re- 45 moved therefrom, and

Fig. 5 is a fragmentary sectional view showing the construction of the handle of the device.

In carrying out the invention, my im- 50 proved device is formed with a hollow, preferably cylindrical, handle 10 which may be formed of metal, wood, or other suitable material, and is closed at its outer end by a screw cap 11. The handle may, of course, 55 be varied in length and diameter as desired. Detachably secured to the inner end of the

handle by a bayonet slot connection is a blade holder 12 locked in position by a thumb screw 12' threaded into the handle. This blade holder is preferably formed from 60 a single piece of suitable resilient sheet metal bent into arcuate shape in cross section so that the said holder is substantially semi-cylindrical to fit around the inner terminal of the handle. Formed in the bottom portion of the 65 holder at each side of a longitudinal medial line therethrough are outwardly diverging longitudinal blade receiving slots 13 which open through the outer end of the holder. These slots thus, as particularly brought out 70 in Figs. 2 and 4 of the drawings, incline downwardly and inwardly toward the inner end of the blade holder and define an intermediate blade receiving portion 14 tapering from the outer end of the holder toward its 75 inner end. Struck from each of the side edges of the blade receiving portion is a series of longitudinally spaced blade gripping 80 tongues or fingers 15 which, as particularly shown in Fig. 3, are offset inwardly within 85 the holder. The tongues of each series are of equal length and aline at their points of juncture with the blade receiving portion so that consequently, the blades of said series respectively, are inclined in conformity 90 with the inclination of the blade receiving slots. As will be seen, in view of the preceding description, the blade holder of the present invention embodies a very simple 95 structure and may be struck at one operation from a single piece of suitable sheet metal.

In connection with the blade holder, I employ oppositely presented blades 16 suitably sharpened at their outer longitudinal edges 95 and provided at their inner longitudinal edges with longitudinally disposed ribs 17. These ribs are preferably formed, in each instance, by bending the metal of the blade over upon itself. The blades are removably 100 fitted within the blade receiving slots 13 and rest at their inner margins upon the blade receiving portion 14 of the holder, to be firmly held in position by the series of tongues 15 engaging over the ribs 17 of the 105 said blades. In this connection it will be observed upon reference to Fig. 3 that the tongues 15 are bent to snugly fit around the said ribs and will consequently securely engage with the blades to prevent any teetering thereof as well as to prevent accidental 110 displacement of the blades. Since, as previ-

ously described, the series of tongues are inclined or converge to conform with the convergence of the blade receiving slots, the blades will, therefore, be supported upon the 5 blade receiving portion of the holder to incline downwardly and inwardly with the slots from the outer end of the holder toward its inner end. Owing to this inclination of the blades, a shearing cut may, as 10 will be readily understood, be easily attained in the practical use of the device. The blades are, of course, of a width, as particularly brought out in Fig. 3, to project through the blade receiving slots laterally 15 with respect to the holder so that the cutting edges of the blades will be exposed for use. However, it is to be noted that the portions of the holder above the blade receiving slots will overhang the cutting edges of the 20 blades. Such portions of the holder will, therefore, provide guards 18 for the blades and will be disposed to contact with the face, in the operation of shaving, to prevent accidental cutting of the face. In order that a 25 supply of blades may be carried about with the device, the handle 10 is made hollow to receive such supply. Furthermore, this handle is thus adapted to receive the blade holder so that the device may accordingly be 30 collapsed to provide a neat and small article of luggage.

It will, therefore, be seen that I have provided a particularly simple and compact structure for the purpose set forth, while at 35 the same time the device will be found very efficient and durable in use. Furthermore, the device is of such nature that it may be manufactured and sold at minimum cost.

Having thus described the invention, what 40 is claimed as new is:

1. A safety razor including a segmental blade holder constructed from a single piece

of material bent into substantially concavo-convex form and having a longitudinally extending slot therethrough defining a blade 45 receiving portion at one side of the slot and a guard at the opposite side of the slot, and yieldable means fixed upon the blade receiving portion and adapted to engage the inner margin of a cutting blade for securing the 50 blade stationary upon the blade receiving portion seating against the inner side face thereof and projecting at its outer margin through said slot beneath the guard.

2. A safety razor including a segmental 55 blade holder constructed from a piece of sheet metal bent into substantially concavo-convex form and provided with longitudinal blade receiving slots therethrough converging toward the inner end of the holder and defining a blade receiving portion between the slots and guards at the outer sides of the 60 slots, and means carried by opposite margins of the blade receiving portion for securing cutting blades stationary against the inner 65 side face thereof and inclined longitudinally of the blade receiving portion to project through said slots beneath the guards.

3. A safety razor including a curved blade 70 holder constructed from a single piece of resilient material having a slot formed therethrough and opening through one end of the holder to define a blade receiving portion at one side of the slot and a resilient guard at the opposite side of the slot free at its outer 75 extremity, and means carried by the blade receiving portion for securing a blade stationary against the inner side face thereof projecting through said slot beneath the 80 guard whereby the free extremity of the guard may be flexed relative to the cutting edge of the blade.

In testimony whereof I affix my signature.

ARTHUR J. BAXTER. [L. s.]
